UNITED STATES PATENT OFFICE

2,682,188

RAILROAD TRACK WASHER HOLDER FOR
POWER WRENCHESClifford Ferrell, Little Rock, Ark., assignor to
Woodings-Verona Tool Works, Verona, Pa., a
corporation of Pennsylvania

Application October 8, 1952, Serial No. 313,717

6 Claims. (Cl. 81—54)

1

This invention relates to power wrenches for tightening nuts on railroad track bolts, and more particularly to means for preventing a non-circular washer from turning on such a bolt during the nut tightening operation.

In Patent No. 2,552,655 there is shown a power wrench for tightening nuts on bolts extending through railroad track rails at their joints. Such a wrench includes a socket member that fits over the nut and adjoining end of the bolt, and an endless drive chain for rotating the socket member to tighten the nut on the bolt. In Patent No. 2,247,959 there is shown a rectangular leaf spring washer that is often applied to track bolts before the nut is screwed on. Such spring washers are formed for controlling the tension that is put on the bolts by the tightened nuts. The washers are compressed between the nuts and the rail joint bars. When the nuts are tightened by a power wrench there is a tendency for these washers to turn on the bolts during the tightening operation, with the result that the washers will not extend lengthwise of the rail unless a workman holds them in position while the wrench is operating.

It is among the objects of this invention to provide an attachment for power track wrenches which will keep leaf spring washers from turning on track bolts as the nuts are tightened.

In accordance with this invention, the attachment or washer holder has a body that is formed for connection to a power wrench near the inner end of the wrench's rotatable socket member. A projection is joined to the body and is adapted to project outwardly beyond the outer end of the socket member and to overlie a leaf spring washer located between a track rail and a track bolt nut in the socket member. This projection keeps the washer from turning on the bolt as the nut is tightened by the wrench. Preferably, there are two projections or prongs which are laterally spaced for engaging the opposite ends of the top of the washer.

The invention is illustrated in the accompanying drawings, in which Fig. 1 is a vertical section through the operating end of a power track wrench shown tightening a nut on a track bolt; Fig. 2 is a fragmentary horizontal section taken on the line II—II of Fig. 1; Fig. 3 is an end view of a socket member and washer holder taken on the line III—III of Fig. 2; Fig. 4 is a perspective view of a modified washer holder; and Figs. 5, 6 and 7 are views similar to Figs. 1, 2 and 3, respectively, showing another embodiment of the invention applied to a different type of power wrench.

2

Referring to Figs. 1, 2 and 3 of the drawings, a pair of railroad track rails 1 and 2 are spliced end to end in conventional manner by means of splice bars 3, through which ends the rail bolts 4 extend. Slidably mounted on the threaded end of each bolt is a leaf spring washer 6, such as shown in Patent No. 2,247,959. This washer is compressed against the adjoining splice bar by a nut 7 screwed on the bolt. The nut is started on the bolt by hand, and then the chuck or socket member 8 of a power wrench is slipped over the nut and turned mechanically to tighten the nut on the bolt. The wrench shown is like the one disclosed in Patent No. 2,552,655, to which reference is made for a full description. It is sufficient here to point out that from one end of the frame 11 of the wrench an inclined arm 12 extends downward beside the track. Rotatably mounted in the lower end of the arm is a sprocket shaft 13 that is driven by endless chains 14 from a drive shaft 16 journaled in the upper end of the arm. The opposite ends of the lower sprocket shaft are square and project into square holes 17 in the inner ends of a pair of the socket members 8, thus forming universal joints. The outer end of each socket member is provided with an opening 18 for receiving the nut 7 on the track bolt. As shown in Fig. 2, the socket members are inclined to the axis of sprocket shaft 13, so that regardless of which side of a rail the arm 12 is swung down beside the axis of the socket member next to the rail will be perpendicular to the rail.

Each socket member 8 is held on the adjoining end of sprocket shaft 13 by means of a vertical retaining plate 20 that has an upwardly extending central recess 21 (Fig. 3) in its lower portion, which permits it to straddle the socket member in an annular groove 22 with which the socket member is provided. The opposite edges 40 of the plate fit in vertical slots 23 in the lower part of arm 12 at opposite sides of the socket member. The plate is slidably mounted in these slots and the socket member groove, but is normally prevented from being lifted out of position by a bar 24 at its upper end. This bar is loosely mounted on a rod 26 that extends through the arm, and the upper end of the bar is pressed toward the arm by means of a coil spring 27 on the rod. Just below the rod the arm extends 50 across an abutment 28, so that the lower end of the bar normally is swung outward away from the arm. This lower end is provided with a pin 29 that projects into a hole 30 in the upper end of the retaining plate. When it is desired to lift 55 the plate out of position, the lower end of the bar

can be pushed in toward the arm to release the pin from the hole.

It is a feature of this invention that while the nut is being tightened on the bolt the rectangular washer is prevented from rotating on the bolt and thereby turning out of its proper position. This desirable result is accomplished by a washer holder that is fastened to retaining plate 20. This holder is formed from a metal plate that is cut and bent to the desired shape. The holder has a body 31 provided with a vertical upper portion that has a pair of laterally spaced openings 32 for receiving a couple of screws 33 extending through the upper part of the retaining plate. The heads of the screws may be countersunk in the plate. Nuts 34 are screwed on their opposite ends to fasten the washer holder to the plate. Preferably, openings 32 are vertical slots which permit the elevation and angle of the holder relative to the retaining plate to be adjusted as necessary. The body of the holder has a lower portion which extends outwardly away from the retaining plate above the underlying socket member 18. From the opposite ends of this horizontal body portion a pair of parallel fingers or prongs 35 extend outwardly and beyond the outer end of the socket member. The outer ends of the prongs are bent downward far enough to substantially engage the top of the spring washer 6 at its opposite ends. These prongs prevent the washer from turning on the bolt while the nut is being tightened. This means that the operator of the wrench does not have to pay any attention to the washer after the wrench has been placed in operating position. When the wrench is removed from the nut, the washer will be in correct position relative to the splice bar behind it.

Instead of a washer holder that can be applied to existing socket retaining plates 20 on the power wrench, a unit can be formed which is a combination holder and retaining plate and which can be substituted for present retaining plates. Such a unit is shown in Fig. 4. The retaining plate portion 36 of this unit is the same shape as the retaining plate described above, but the body of the washer holder has only a horizontal portion 37 and that is welded to the outer face of the plate. At opposite ends of this body there are prongs 38 which will extend out past the end of a socket member into a position for preventing a leaf spring washer from turning.

Another type of power wrench on the market does not use a chain drive for rotating the socket members. It uses a drive shaft that is coupled to the socket members through a gear box. Such a gear box 41 is shown in Figs. 5, 6 and 7. The ends of the box are circular and have annular end covers 42 fastened to them by cap screws 43. The rotatable chucks or socket members 44 extend out through these covers and are adapted to screw nuts on bolts in the same way as previously described herein. The washer holders that are used with this type of wrench have arched bodies 45 that fit flat against the upper portions of the end covers after the cap screws in that location have been removed. Each arched body is provided with holes aligned with the holes in the cover behind it so that cap screws 70 can be inserted in the aligned holes to fasten the body to the gear box. In order to provide room for three cap screws in body member 45, the opposite ends of the body extend downward to points below the top of the socket member.

From these ends parallel prongs 46 extend outward along the opposite sides of the socket member and beyond its outer end to positions directly above the ends of leaf spring washer 6. As the prongs leave the arched body of the holder they are inclined upward for a short distance so that their outer ends will be at the proper level.

In case any of these holders are to be applied to upright wrench surfaces that are not parallel to a rail, one prong can be made longer than the other to compensate for the angle. Also, if the retaining plate is tilted, the outer end of the lower prong can be bent down to a lesser degree than the other one, if necessary.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. A holder for preventing rotation of a leaf spring washer on a railroad track bolt while a nut is being tightened against the washer by the rotating socket member of a power track wrench, said holder comprising a body formed for attachment to such a wrench near the inner end of its socket member, and a projection joined to said body and adapted to project outwardly beyond the outer end of the socket member, whereby to overlie a leaf spring washer between a track rail and a track bolt nut in said socket member to keep the washer from turning on the bolt.

2. A holder for preventing rotation of a leaf spring washer on a railroad track bolt while a nut is being tightened against the washer by the rotating socket member of a power wrench, said holder comprising a body formed for attachment to such a wrench near the inner end of its socket member, and a pair of laterally spaced prongs joined to said body and adapted to project outwardly beyond the outer end of the socket member, whereby to overlie a leaf spring washer between a track rail and a track bolt nut in said socket member to keep the washer from turning on the bolt.

3. A holder for preventing rotation of a leaf spring washer on a railroad track bolt while a nut is being tightened against the washer by the rotating socket member of a power wrench, said holder comprising a vertical body provided with fastener-receiving openings for attaching it to a vertical surface of such a wrench near the inner end of its socket member, and a pair of laterally spaced prongs joined to the lower part of said body and adapted to extend outwardly along the upper part of the socket member and beyond its outer end, whereby to substantially engage the top of a leaf spring washer between a track rail and a track bolt nut in said socket member to keep the washer from turning on the bolt.

4. A holder for preventing rotation of a leaf spring washer on a railroad track bolt while a nut is being tightened against the washer by a rotating socket member projecting from the circular gear case of a power wrench, said holder comprising an arched body provided with a plurality of laterally spaced fastener receiving openings for attaching it to the gear case of such a wrench above the inner end of its socket member, and a prong joined to each end of said body and adapted to extend outwardly along the upper

part of the socket member and beyond its outer end, whereby to substantially engage the top of a leaf spring washer between a track rail and a track bolt nut in said socket member to keep the washer from turning on the bolt.

5. A holder for preventing rotation of a leaf spring washer on a railroad track bolt while a nut is being tightened against the washer by the rotating socket member of a power track wrench, said holder comprising a vertical plate provided with a central recess extending upwardly from its lower edge adapted to receive the inner end of the socket member of a power wrench, a body member projecting from the plate above said recess, and a pair of substantially parallel prongs projecting from the ends of said body member far enough to extend beyond the outer end of the socket member, whereby to overlie a leaf spring washer on a track bolt.

6. The combination with a power track wrench having a rotating socket member for receiving and tightening a nut on a railroad track bolt, of

a washer holder comprising a body attached to the wrench near the inner end of said socket member, and a pair of laterally spaced prongs joined to said body and extending outwardly along the upper part of the socket member and beyond its outer end a short distance, whereby to substantially engage the top of a leaf-spring washer between a track rail and said nut to keep the washer from turning.
